ATTORNEYS.

UNITED STATES PATENT OFFICE.

CHARLES M. JACOBS, OF LONGMEADOW, MASSACHUSETTS.

WINDOW-SASH-LOCKING DEVICE.

1,344,038.

Specification of Letters Patent. Patented June 22, 1920.

Application filed November 4, 1919. Serial No. 335,728.

To all whom it may concern:

Be it known that I, CHARLES M. JACOBS, a citizen of the United States of America, residing at Longmeadow, in the county of 5 Hampden and Commonwealth of Massachusetts, have invented a certain new and useful Improvement in Window-Sash-Locking Devices, of which the following is a specification.

This invention relates to improvements in an attachment for window sashes, the object of which is to provide a device for securely locking the upper and lower sashes together so that either one or both may be 10 moved from the closed position, that is to say, the upper one may be moved downward, or the lower one moved upward, or the two may be moved together. In order to prevent the window from being opened and 15 at the same time provide proper ventilation, the device herein shown is applicable. It comprises a member, preferably U-shaped, adapted to be secured to the upper sash and a second member adapted to be secured to 20 the upper or mid-rail of the lower sash and so attached that it may be swung or rotated into engagement with the U-shaped member of the upper sash. Means is also provided for drawing the two sashes toward each 25 other when in locking engagement.

Referring to the drawings:

Figure 1 is a perspective view showing the two sashes in closed position, the locking or rotating part of the device being turned 30 in parallel relation to the mid-rail.

Fig. 2 shows the device when in use and with the locking or rotative part turned toward the upper sash and into locking engagement with the U-shaped member.

Fig. 3 is a perspective view of the U-shaped member which is attached to the upper sash showing the ears and the cut-out part for receiving the tongue portion of the rotatable part.

Fig. 4 is a detail view of the latch part.

Referring to the drawings in detail: 1 designates the upper sash and 2 the lower sash. Secured to one of the uprights or side portions 3 of the sash 1 is a U-shaped member 4 having upper and lower parallel plates 5 and 6 that are connected together by the integral portion 7 which is formed with the horizontally extending ears 8 and 9 having openings 10 for receiving screws or other devices for attaching the same to the part 3 at any suitable distance from the

mid-rail. The lower plate 6 is formed with an opening or cutaway portion 11. 8' and 9' designate ears that are located in a vertical position above and below the plates 5 and 6 and having openings 10' for the attaching screws. These ears are used if the thickness of the sash is not sufficient to receive the ears 8 and 9. The screws are then passed through the openings 10'. 65

Referring to the latching device which is shown in detail in Fig. 4, this device comprises a barrel portion 12 having the wings 13 and 14 and an opening 15 therethrough for pivotally attaching the same to the upper surface of the mid-rail 16 as shown in Figs. 1 and 2. 17 designates an integral arm having a projection or enlargement 18 which is formed with a shoulder 19. This arm 17 swings into the space between the 75 plates 5 and 6, shown in Fig. 2, when in locking use and the enlarged portion 18 then drops into the cut-out part 11 of the lower plate 6 and the shoulder portion 19 engages the inner edge 20, it being understood that the rigid arm 17 slightly bends the flexible plate 6 downward in order to lock the two sashes together and to prevent their being shaken apart by an intruder. It is clear that the two sashes may be moved 80 as a unit when they are locked together or each of the sashes may be moved separately when they are unlocked.

What I claim is:

1. In a device for the purpose described, 90 comprising a member substantially U-shaped and having plates spaced from each other and designed for attachment to one of the upright side rails of the upper sash of a window and the open or entrance end of 95 the spaced plates of the member extending in a direction toward the opposite upright side rail, a second member adapted to be pivotally attached to the mid-rail of the lower sash and having an extension for 100 entering the open end of said member, which is secured to the upper sash, and interlocking snap devices between the plates and the second member.

2. A device for the purpose described, 105 comprising two members, one being integral and permanently secured to the upper sash and having a slightly flexible portion, the other member being movably secured to the lower sash and having a rigid L-shaped 110 arm formed with a projection or boss to engage a recess in the flexible portion of the

member on the upper sash for locking the two sashes together to permit said sashes to be moved together as a unit, as described.

3. A device for locking the upper and lower sashes of a window together for permitting either one of the sashes to be moved from normal or closed position and comprising a member having a base portion, ears therein for attachment to one of the side rails of the upper sash, and having spaced parallel plates in horizontal planes

that are connected to the base portion, one of the plates being flexible and having a cut-out part, a rigid member having a locking flat blade mounted on the lower sash 15 and formed with an enlarged portion for snapping into and engaging the cut-out portion of the integral flexible plate; whereby the two sashes may be locked together, as described.

CHARLES M. JACOBS.
